[57] CLAIM

The ornamental design for a vehicle cover, as shown and described.

DESCRIPTION

FIG. 1 is a top plan view of the vehicle cover of the present invention;

FIG. 2 is a bottom plan view of the vehicle cover of FIG. 1; FIG. 3 is a left side plan view of the vehicle cover of FIG. 1;

FIG. 4 is a right side plan view of the vehicle cover of FIG. 1;

FIG. 5 is a front plan view of the vehicle of FIG. 1;

FIG. 6 is a back plan view of the vehicle cover of FIG. 1; and,

FIG. 7 is a right side view of the vehicle cover of FIG. 1 installed.

The broken line showing of environment is for illustrative purposes only and forms no part of the claimed design.
